Primary Examiner — Ricky Pham(74) *Attorney, Agent, or Firm* — Alexander D. Raring**CLAIM**

The ornamental design for a food processor base, as shown and described.

DESCRIPTION

FIG. 1 is a top, front and right side perspective view of a food processor base showing the new design;

FIG. 2 a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an perspective view thereof.

Broken lines illustrate environmental structure. The broken lines in the drawings are included for illustrative purposes only and form no part of the claimed design.
